UNITED STATES PATENT OFFICE

JACOB NORTHCUTT, OF LONG BEACH, CALIFORNIA

VEGETABLE KNIFE

Application filed March 27, 1929. Serial No. 350,266.

This invention relates to improvements in vegetable knives and particularly to an attachment adapted to be applied to a vegetable knife to facilitate its use. The invention may be considered as an improvement over the construction disclosed in my pending application, Serial No. 177,774, filed March 23, 1927.

An object of the present invention is to provide an improved construction adapted to be applied to a vegetable knife which improved construction is so constructed that it may be applied by slipping it laterally on the blade of the knife so that it is applied over the edge of the knife, forming a guide determining the thickness of peelings peeled from vegetables by the knife.

Another object of the invention is to provide an attachment adapted to be applied to vegetable knives and the like which has a guide roller adjustably mounted by an improved form of adjustment which will facilitate adjusting the guide roller to vary the thickness of the peelings or slices.

A further object of the invention is to provide an attachment for vegetable knives which provides for the application of a part enabling the knife to cut a plurality of slices simultaneously from a vegetable.

With the foregoing and other objects in view which will be made manifest in the following detailed description and specifically pointed out in the appended claims, reference is had to the accompanying drawings for an illustrative embodiment of the invention, wherein:

Fig. 1 is a top plan view of a vegetable knife illustrating the attachment as having been applied thereto.

Fig. 2 is a view in side elevation of the same, parts being broken away and shown in vertical section.

Fig. 3 is a bottom plan view of the knife shown in Fig. 1.

Fig. 4 is a view in end elevation taken in the direction of the arrow 4 upon Fig. 2.

Fig. 5 is a vertical section taken upon the line 5—5 upon Fig. 2.

Fig. 6 is a vertical section taken upon the line 6—6 upon Fig. 2.

Fig. 7 is a view in side elevation of the knife illustrating the manner in which the additional part is applied to enable the knife to cut a plurality of slices simultaneously from a vegetable.

Fig. 8 is a perspective view of the frame part of the attachment.

Fig. 9 is a perspective view of the guide roller.

Fig. 10 is a perspective view of the part adapted to be applied to the device in cutting the plurality of slices.

Referring to the accompanying drawings wherein similar reference characters designate similar parts throughout, the vegetable knife to which the device is adapted to be applied may be of any conventional construction. It is shown as having a blade 10 which is flat and has a straight cutting edge 11. The handle of the knife is indicated at 12. The invention comprises a frame having a top bar 13 which is supported by upright standards 14 and 15, the bottoms of which are bent laterally and formed into U-shaped clamps 16 and 17. The clamps 16 and 17 are open at their rear ends so that the frame can be slipped laterally onto the blade 10 of the knife from the cutting edge 11. By the improved construction it will be appreciated that the frame is applicable to any conventional form of knife and that the shape of the blade may vary without requiring variations in the construction of the frame to enable its application.

Vertical slots 18 and 19 are formed in the standards or uprights 14 and 15 forwardly of the top bar 13. As clearly shown in Fig. 8 the slot 18 has its rear side serrated as indicated at 20 while the slot 19 has its forward side serrated or notched as indicated at 21. The vertical slots 18 and 19 are adapted to receive the pintle 22 of a guide roller 23. The ends of the pintle which is preferably formed of stiff wire, are bent upwardly as indicated at 24 and then bent downwardly as indicated at 25 and finally bent inwardly as indicated at 26. The inwardly bent ends 26 are offset with respect to the pintle 22, i. e. the inwardly bent end 26 which is disposed within the slot 18 is offset rearwardly with re-

spect to the pintle so that it bears against the serrated side 20 of the slot. In a similar manner the inwardly bent end 26 on the end of the pintle 22 which is disposed in the slot 19 is offset forwardly with respect to the pintle so that it bears against the forward serrated side 21 of the slot. The edges of the inwardly bent ends 26 are preferably sharpened as shown in Fig. 6 so that they will fit into the notches or serrations in the sides of their respective slots. This construction serves to adjustably mount the guide roller 23 in the slots 18 and 19. To adjust the roller with respect to the edge 11 of the knife blade 10 the inwardly bent ends 26 are pressed so as to bring them in alignment with the pintle 22 thus moving the ends 26 out of the notches and enabling the pintle and guide roller to be vertically shifted. On releasing the ends 26 they will immediately spring laterally and engage their respective notches in the sides of their respective slots.

By the improved construction it will be noted that the guide roller can be adjusted with respect to the knife edge 11 but at all times the roller is in parallel spaced relation to the knife edge and arranged slightly forwardly of the knife edge. In using the knife the roller rolls upon the exterior surface of the vegetable and serves to guide the cutting edge of the knife so that the knife blade will remove a peeling from the vegetable. By adjusting the roller the thickness of the peeling can be varied and the knife can be advantageously employed in slicing vegetables.

The drawing illustrates the roller in the position so that if the user is right handed the stroke of the knife in peeling will be toward the user. I find that by reversing the position of the frame so that the roller will be on that side of the blade shown in Fig. 3 that the knife can be stroked away from the person of the user. By using the device in this manner the knife can be stroked against the surface of the vegetable very quickly and caused to remove the peelings quite fast.

The improved construction enables the application of an attachment shown in Figs. 7 and 10. This attachment comprises a base 30 having its forward edge tapered as indicated at 31 and having forwardly extending arms 32 and 33. The outer side edges of the arms are tapered as indicated at 34 and are adapted to slide inwardly into the frame between the blade 10 and the bases of the standards 14 and 15. The upstanding stops 35 at the forward ends of the arms engage the forward edges of the standards and limit the inward movement of the attaching part. On the base 30 there are upstanding knives 36, the upper ends of which have their backs cut away as indicated at 37 and are receivable in notches 38 formed in the top bar 13 on the frame. When this device is applied the roller

23 may or may not be removed. When a slice is cut by the knife blade 11 from the vegetable the slice will pass rearwardly until it engages the knives 36 which cut the slice into strips.

From the above described construction it will be appreciated that an improved vegetable knife attachment is provided which is so constructed that it may be applied laterally across the cutting edge of any suitable form of knife thus making the device universally applicable. The improved construction also has a novel adjustment of the roller which enables the roller to be easily and quickly adjusted into any desired position to vary the thickness of the peelings or slices cut from vegetables.

Various changes may be made in the details of construction without departing from the spirit or scope of the invention as defined by the appended claims.

I claim:

1. An attachment for vegetable knives comprising a frame attachable to a knife blade, said frame having a pair of slots formed therein, said slots each having a serrated side, and guide means adjustable in the slots and having portions engageable upon the serrated sides.

2. An attachment for vegetable knives comprising a frame attachable to a knife blade, said frame having a pair of slots formed therein, said slots each having a serrated side, a pintle extending through the slots and having returned ends which are offset so as to bear against the serrated sides, and a guide roller rotatably mounted upon the pintle.

3. An attachment for vegetable knives comprising a frame having a top bar, standards supporting the top bar, U-shaped clamps arranged at the bases of the standards, said clamps being open at their rear ends so as to be receivable over the edge of a knife blade, said standards having slots formed therein, each slot having a serrated side, a pintle extending through the slots and having returned ends which are adapted to bear against the serrated sides, and a guide roller rotatably mounted upon the pintle and held in spaced parallel relation to the cutting edge of the knife blade.

In testimony whereof I have signed my name to this specification.

JACOB NORTHCUTT.
